UNITED STATES PATENT OFFICE.

NOAH T. REMY, OF MILTON, INDIANA.

CORD-HOLDER FOR GRAIN-BINDERS.

SPECIFICATION forming part of Letters Patent No. 314,056, dated March 17, 1885.

Application filed October 22, 1883. (No model.)

To all whom it may concern:

Be it known that I, NOAH T. REMY, a citizen of the United States, and a resident of Milton, in the county of Wayne and State of Indiana, have invented a certain new and useful 5 Improvement in Twine-Holders for Grain-Binders, of which the following is a specification.

My invention relates to an improvement in 10 cord-holders for grain-binders which are designed especially to be used in connection with the binder mechanism shown in Letters Patent granted J. F. Appleby, February 18, 1879, No. 212,420, with the various modifications 15 thereof in general use, and being improvements thereon, all of which will be fully explained in the description of the accompanying drawings.

Figure 1 represents a bottom view of my 20 improved twine-holder. Fig. 2 is an edge view of the shoe portion thereof. Fig. 3 is a rear elevation, and Fig. 4 is a top plan view of the entire holder.

The letter A designates a twine-holder disk 25 mounted on a shaft and revolving in a plane at right angles to the path of the binder-arm, in the usual manner. This disk is employed in the Appleby binders in general use.

a represents notches cut in the periphery 30 of disk A, into which notches the cord or twine is successively placed by the needle and tucking mechanism, and between which notches and the shoe it is gripped while being drawn around a bundle while the knot is being tied and the string being cut off.

B represents a spring twine-holder shoe provided with flanges b c, which are of a sufficient 35 distance apart to form a groove or space, d, and between which flanges the disk A and the twine are carried when the disk A is revolved.

D represents a spring which holds the shoe B against the notched disk A. A hole, e, is pierced in the shank of the shoe for pivoting it in the usual manner.

C represents the ratchet, which is rigidly secured to the disk A in the ordinary manner.

In Fig. 1 is shown the position of the parts when the twine has been placed in the notch a of the disk A ready for the movement of the 40 disk A to carry the twine forward in position for tying. i represents the end of the cord

which has been cut off in binding a previous bundle.

Fig. 4 represents the position of the disk A and the cord in the position in which the cord 55 is held when the knot is being tied or drawn taut and twine cut off.

It has been customary to make the flanges b c of equal length; but a great difficulty has been experienced in the use of such flanges on 60 the shoe, as the cut end of the cord is jammed in between the flanges of the shoe. I have discovered that by cutting away the metal or flange c a sufficient distance in rear of the point l the end i of the twine would be easily discharged and all of the difficulty hitherto experienced efficiently obviated. The amount of metal cut off from the flange c depends upon 65 the size of the notch a and the size of the cord h. It should, however, be cut away sufficiently 70 to be in the rear of the point l of notch a. (Shown in Fig. 1.) The shape of the sloping or cut-away of the flange c is not material provided it is sufficient to allow the cord to pass out of the end of the shoe without jamming 75 against the flange c when it is in position for discharging the end i. When the flange c is beveled off in this manner, no adjustment of the spring D is required in the use of the improved cord-holder with different thicknesses 80 or sizes of twine.

I claim—

1. In a cord-holder for grain-binders, the combination of the rotary disk with the shoe having flanges to embrace the edge of the disk, 85 the flange on the side of the disk away from the knotter being cut away at its rear end, substantially as described.

2. In a cord-holder for grain-binders, the combination of the notched rotary disk with 90 the grooved or flanged shoe, the flanges of which straddle or embrace the edge of the disk, and the flange on the side of the disk away from the knotter cut away at its rear end, substantially as described.

In testimony whereof I have hereunto set my hand.

NOAH T. REMY.

Witnesses:

JNO. E. JONES,
A. GLUCHOWSKY.

Correction in Letters Patent No. 314,056.

It is hereby certified that Letters Patent No. 314,056, granted March 17, 1885, upon the application of Noah T. Remy, of Milton, Indiana, for an improvement in "Cord-Holders for Grain-Binders," should have been issued to *The Dorsey Machine Company*, of same place, assignee of the entire interest in said invention; that the proper corrections have been made in the files and records of the case in the Patent Office, and should be read in the Letters Patent to make it conform thereto.

Signed, countersigned, and sealed this 2d day of June, A. D. 1885.

[SEAL.]

H. L. MULDROW,
Acting Secretary of the Interior.

Countersigned:

ROBT. B. VANCE,
Acting Commissioner of Patents.
